THOMAS B. RIDER, OF LOS ANGELES, CALIFORNIA, ASSIGNR OF ONE-HALF TO
ADOLPHE DANZIGER, OF LOS ANGELES, CALIFORNIA.

X-RAY TUBE.

1,352,630.

Specification of Letters Patent. Patented Sept. 14, 1920.

Application filed December 30, 1918. Serial No. 268,940.

To all whom it may concern:

Be it known that I, THOMAS B. RIDER, a citizen of the United States, residing at Los Angeles, in the county of Los Angeles and 5 State of California, have invented new and useful Improvements in X-Ray Tubes, of which the following is a specification.

My invention relates to improvements in X-ray tubes.

10 One of the objects of this invention is to provide effective means for regulating the vacuum within the tube.

Another object is to provide a device with 15 means of varying strength to produce various degrees in the gas storage so as to effect a regulating and control of the vacuum of the X-ray tube.

Another is to provide a combination of 20 chemicals by which gases can be produced that will be effective according to the desired degree of vacuum in the tube.

Other objects will appear from the following description and appended claims as 25 well as from the accompanying drawing, in which—

The figure is a side elevation of an assembly of an X-ray tube with my device in position.

The glass globe 1 forms the main body of 30 the X-ray tube, which has to be maintained under a proper degree of vacuum for X-ray effectiveness. The cathode 2 is disposed within one of the extensions of the main body 1. An anode 3 is disposed in practically the center of the body 1 with its outside connection connected by the wire 14 to the outside connection end of the auxiliary anode 4. 5 designates an extension of the main body to which my device is applied. 35 A suitable number of side extension ends 6, 8 and 10 are communicating with the extension end 5 and thereby with the main body 1 of the X-ray tube, and the whole device (side extensions 6, 8 and 10; and the extension 5 with the body) is properly sealed airtight to facilitate an operation of the X-ray tube under vacuum as required. Each 45 of the extensions 6, 8 and 10 is provided with a suitably prepared chemical, as indicated at 7, 9 and 11.

To make an operation with so many or more chemical-containers possible and effective in the desired manner, it is preferable that the chemicals in one container be dif-

ferent in strength from those in another container. 55

It is essential that X-ray tubes be provided with vacuum regulating devices to meet the constantly changing vacuum in the X-ray tubes. Thus far, nearly all present 60 types of X-ray tubes have a single regulating device exclusively for reducing the vacuum. This regulator cannot be too sensitive during the operation on account of the danger of reducing the vacuum beyond 65 X-ray effectiveness. Also, when the chemicals that produce the regulating gases have become exhausted, the resistance of the vacuum to the electrical current grows so 70 strong that operation for X-ray work is impossible; the vacuum in such a tube must then be destroyed, a new regulator sealed on and the tube reëxhausted. And as, furthermore, newly exhausted X-ray tubes are 75 invariably of a high vacuum, it is evident that the regulator must come into immediate use to achieve efficient X-ray work. It is equally evident that unless there is a means to prevent a too great reduction of the vacuum the tube will be affected adversely for efficient X-ray work. 80 Jointly with this necessity is even the greater need for providing the X-ray tube with auxiliary regulators to prevent the destruction of the entire vacuum, the sealing on of a 85 new regulator and the reëxhausting of the tube itself, since one regulator cannot possibly achieve all the various effects necessary to bring about an efficient and reliable vacuum for a working basis. 90

To combine all these needful improvements, I have invented a cluster of a suitable number of regulators so arranged as to be responsive not only to the vacuum within the tube when a regulator has become exhausted and a reduction of the vacuum is needed, but responsive also to the varying conditions of the vacuum in the tube when such vacuum does not need any reduction but stabilization, that is, to maintain a degree of desired vacuum. I am able to achieve this by passing an electrical current through one, two, or more regulators containing various chemicals, yielding certain gases which, when released and blended, 95 will bring about a stabilizing effect upon the vacuum within the X-ray tube. 100

While, therefore, as a rule only one of the

regulators at one time will be used and the others consecutively or alternately to reduce the vacuum, two or more may come into operation when a stable vacuum rather than a reduction of the same be desired, the effect of which will be as already mentioned.

It will readily be understood that as many more regulators as desired for reducing the vacuum can be added to the cluster the object of which is to afford efficient service without interruption, and thus save time, labor and the reëxhaustion of the X-ray tube, all of which when obviated, tends to prolong the life and the efficiency of the X-ray tube.

The cathode feed wire 12 is shown to the left, and the anode feed wire 15 to the right. A wire arm 13 is joined to the regulator 10 and extended close to the cathode feed wire 12 for passing the electrical current through the chemicals 11 contained in the regulator 10 to regulate the vacuum within the X-ray tube. Other wire arms can be joined in a similar manner, as will easily be understood, to the other regulators consecutively, alternately, or at the same time, just as required to obtain the right effect.

It being understood that for the purpose of admitting the electrical current into two or more regulators to stabilize and maintain the vacuum at a certain degree, wires similar to wire arm 13 can be attached in a suit-

able manner to the respective regulators, thus, while one wire arm, if operated alone, will reduce the vacuum, and the other regulators may be used consecutively for the same purpose, the chemicals may also be blended by affecting two or more of the regulators containing chemicals at the same time and thus blend the gases to regulate the vacuum in the X-ray tube.

Having thus described my invention, I claim:

1. In an X-ray tube, a cluster of a suitable number of regulators each regulator containing chemicals of different strength from the chemicals in the others.

2. In an X-ray tube, a cluster of a suitable number of regulators each regulator containing chemicals of different strength to the strength of the chemicals in the others, and means for connecting each of the regulators with the source of the electrical current for blending the obtained gases from the chemicals in the different regulators for the purpose of stabilizing the vacuum and maintaining a desired degree of vacuum in the X-ray tube.

In testimony whereof I hereunto affix my signature in the presence of two witnesses.

THOMAS B. RIDER.
